Primary Examiner — David Muller(74) *Attorney, Agent, or Firm* — Schwegman Lundberg & Woessner, P.A.(57) **CLAIM**

The ornamental design for a catheter cover, as shown and described.

DESCRIPTION

FIG. 1 is a top perspective view of a catheter cover of the present invention;

FIG. 2 is a left side elevation view of the catheter cover;

FIG. 3 is a right side elevation view of the catheter cover;

FIG. 4 is a front elevation of the catheter cover;

FIG. 5 is a back elevation of the catheter cover;

FIG. 6 is a bottom plan view of the catheter cover;

FIG. 7 is a top perspective view of a catheter cover according to another embodiment of the present invention; and,

FIG. 8 is a bottom plan view of the catheter cover in FIG. 7. The broken and dashed lines of FIGS. 1-4 and 6-8, illustrate portions of the catheter cover that form no part of the claimed design.
